Inventor
GEORGE H. JUNG, JR.

By Murray & Gugelten

Attorneys

UNITED STATES PATENT OFFICE.

GEORGE H. JUNG, JR., OF CINCINNATI, OHIO.

ARCH BRACE.

Application filed November 13, 1924. Serial No. 749,802.

To all whom it may concern:

Be it known that I, GEORGE H. JUNG, Jr., a citizen of the United States of America, and a resident of Cincinnati, in the county 5 of Hamilton and State of Ohio, have invented new and useful Improvements in an Arch Brace, of which the following is a specification.

This invention relates to arch braces of 10 the type disclosed in my co-pending application, Serial No. 720,867.

An object of my invention is to provide a simplified structure wherein the advantages 15 incident to my co-pending application are attained.

Another object of my invention is to provide a device that may be economically produced at a minimum of cost.

These and other objects are attained by 20 the means described herein and disclosed in the accompanying drawings, in which:

Fig. 1 is a perspective view of an arch brace embodying my invention applied to a 25 human foot.

Fig. 2 is a perspective view of a device 30 embodying my invention.

Fig. 3 is an enlarged sectional view on line 3—3 of Fig 2.

Fig. 4 is a plan view of a section of an 35 arch brace embodying my invention.

In the instant invention, similarly to the invention disclosed in my co-pending application, a pad 10 is attached to or carried by an elastic band 11 by means of a single 40 transverse row of stitching 12 whereby to utilize to the maximum all of the elastic qualities of the band 11. The elastic band may be of any desired form and of any suitable material and is elastic transversely of 45 the foot as applied. The pad 10 comprises an upper facing 13 of rubber or other suitable material that is given the desired contour or form for providing the desired support to the arch of the foot 14. The pad 50 or cushion 13 is carried by a fabric base 15 and the stitching 12 is used to secure the

fabric base 15 upon the elastic band 11. The pad 13 may be attached to the fabric base 15 in any suitable manner by being vulcanized thereto or being attached thereto 50 by any suitable adhesive means. The simplicity of the instant disclosure over the structure disclosed in my said co-pending application is readily evident. It will also be readily evident that the device disclosed 55 herein may be manufactured at a minimum cost over the disclosures of a similar nature heretofore made and that the instant device provides a structure wherein the elasticity of the entire band 11 may be utilized yet 60 the pad 10 is securely attached to the elastic band.

What I claim is:

1. An arch brace of the class described comprising an elastic band and a pad carried 65 by the band and secured thereto along a single line extending transversely of the elastic band and substantially centrally of the pad.

2. An arch brace of the class described 70 comprising an elastic band, a pad carried thereby comprising a fabric base and a cushion affixed to the fabric base, and a single row of stitching for affixing the pad to the band, the row of stitching extending 75 transversely of the band and disposed substantially centrally of the fabric base and extending partly into the cushion but not therethrough.

3. An arch brace of the class described 80 comprising an endless elastic band for mounting at the transverse arch of the foot and elastic transversely of the foot, a pad comprising a fabric base and a cushion fixed upon the base, and a row of stitching extending 85 transversely of the band and passing through the fabric base for securing the pad upon the band.

In testimony whereof, I have hereunto subscribed my name this 12th day of November, 1924.

GEORGE H. JUNG, JR.
